(57) **CLAIM**

The ornamental design for a receptacle for a touch member for mobile electronic devices, as shown and described.

DESCRIPTION

FIG. 1 is a left, top and front perspective view of the receptacle for a touch member for mobile electronic devices showing our new design.

FIG. 2 is a front view thereof;

FIG. 3 is a rear view thereof;

FIG. 4 is a top view of thereof;

FIG. 5 is a bottom view thereof;

FIG. 6 is a left end view thereof;

FIG. 7 is a right end view thereof;

FIG. 8 is a lateral cross sectional view thereof, taken along lines 8-8 of FIG. 2; and,

FIG. 9 is a longitudinal cross-sectional view thereof, taken along lines 9-9 of FIG. 6.

1 Claim, 3 Drawing Sheets
